(57) CLAIM

The ornamental design for a tablet computer cover and file folder, as shown and described.

DESCRIPTION

FIG. 1 is a top perspective view of a tablet computer cover and file folder showing my new design.

FIG. 2 is a bottom plan view thereof.

FIG. 3 is a top plan view thereof, shown holding a tablet computer.

FIG. 4 is a right end elevational view thereof.

FIG. 5 is a left end elevational view thereof.

FIG. 6 is a front elevational view thereof.

FIG. 7 is a rear elevational view thereof; and,

FIG. 8 is a top perspective view thereof, shown with an insert sheet.

The broken lines in the drawings are shown for the purpose of illustrating environment only and form no part of the claimed design.
